UNITED STATES PATENT OFFICE.

JOHN B. COLLIN, OF ALTOONA, PENNSYLVANIA.

STAND-PIPE.

SPECIFICATION forming part of Letters Patent No. 271,195, dated January 23, 1883.

Application filed May 24, 1882. (No model.)

To all whom it may concern:

Be it known that I, JOHN B. COLLIN, of Altoona, county of Blair, and State of Pennsylvania, have invented new and useful Improvements in Stand-Pipes; and I do hereby declare that the following is a full and exact description of the same, reference being had to the accompanying drawings, and to the letters of reference marked thereon.

10 This invention consists mainly, first, in the special construction of the valve which is employed to control the supply of water to the stand-pipe; and, second, in the combination, with the valve, of certain mechanism for operating the same, the latter being adapted, by means of its construction and location, to be conveniently actuated by the fireman without getting off the tender.

It consists, further, in certain other combinations and in certain details of construction, all of which will be fully described hereinafter.

In the drawings, Figure 1 represents a rear view of the stand-pipe when swung over the track into position to supply water, the counterbalance-weight being omitted to better show the parts, and a side view of the horizontal pipe-sections and the valve mechanism located thereon; Fig. 2, a partial rear view with the counterbalance-weight in place; Fig. 3, a side view of the stand-pipe when swung over the track into position to supply water, the valve-actuating mechanism being shown in the position occupied by it when the valve is closed; Fig. 4, a side view of the pipe-section B, with the waste-cock for emptying the stand-pipe after the main valve has been closed shown in its open position; Fig. 5, an end view of the pipe-section B and the adjacent sections C D E; Fig. 6, a partial side view of the valve and the mechanism for actuating it, the valve being shown in its closed position; Fig. 7, a partial side view of the valve, the same being shown in its open position; Fig. 8, an end view of the safety-valve in its open position; Fig. 9, a side view of the stand-pipe when swung over the track into position to supply water, the valve mechanism being shown in the position occupied by it when the valve is open; Fig. 10, a plan view of the system of levers by means of which connection is made between the valve-stem and the vertically-moving col-

lar of the stand-pipe; Fig. 11, an end view of the valve-stem and its connections, and Fig. 12 various views of the waste-cock mechanism.

To enable others skilled in the art to make my improved stand-pipe, I will proceed to describe fully the construction of the same.

A, Figs. 1 and 6, represents a horizontal pipe-section, by means of which connection is made with the water-main in any proper manner. 60

a represents a branch extending in a vertical direction from the pipe A, the open end of which is closed ordinarily by the safety-valve *a'*, Figs. 6 and 8, as shown.

*a*² *a*² represent rods bolted to the branch *a*, 65 which rods extend upward and furnish, by means of a cross-bar, *a*³, a proper fulcrum for the fixed ends of the levers *a*⁴ *a*⁴, as shown.

*a*⁴ represents a threaded portion near the center of the rods *a*², and *a*⁵ a cross-bar adapted 70 for vertical adjustment on the rods by means of proper nuts, as shown, which bar is provided with a bearing-plate, *a*⁶, as shown.

*a*⁷ represents a spring inclosing the valve-stem *a*⁸, which spring bears at its lower end 75 against the upper face of the valve and its upper end against the bearing-plates *a*⁶, as shown.

B, Figs. 6 and 7, represents a horizontal pipe-section of special form, adapted to contain the main-valve mechanism, which is united at one 80 end to the inner end of the pipe-section A and at the other to the outer end of the curved section C, as shown in Fig. 6.

b represents an inner projecting portion of the pipe-section B, and *b'* an outer enlarged 85 portion surrounding the inner portion, as shown.

*b*² and *b*³ represent the bearing-seats of the valve-openings in the otherwise closed end of portion *b*.

*b*⁴ represents a removable cover adapted to close the opening in the outer portion, *b'*, which is provided with a stuffing-box, *b*⁵, of ordinary construction, as shown. By means of the described construction a water-space is caused 90 to entirely surround the projecting inner portion, *b*, as shown in Fig. 6.

*b*⁶, Fig. 7, represents a hollow cylinder bolted to the lower side of the portion *b'* of the pipe-section B, which is open above, as shown, and 100 is adapted in size and position to extend into the recess *b*⁸ of the valve, as shown in Fig. 6.

b⁷ represents the lower disk of this valve, which is adapted to fit the seat *b²*, and *b⁸* the recess before referred to.

b⁹ represents the upper disk of the valve, which is adapted to fit the seat *b³*, and is provided with the guiding-wings *b¹⁰*, as shown.

b¹¹, Fig. 6, represents the valve-stem, secured at its lower end to the valve in any proper manner, and provided above with a copper tube or pipe, *b¹²*, as shown, by means of which pipe a better protection is afforded against rust.

b¹³, Figs. 6, 10, and 11, represents a cross-bar held by the levers *e⁴*, by means of which the valve-stem *b¹¹* is united to the levers.

b¹⁴, Figs. 4 and 12, represents a tube extending from the pipe-section B, which opens into a cylinder or cock, *b¹⁵*, having an opening, *b¹⁶*, as shown.

b¹⁷ represents a hollow plug within the cylinder, which is provided with oppositely-located openings, as shown.

b¹⁸ represents a lever-arm, by means of which the plug may be revolved when desired, and *b¹⁹* a connecting-rod uniting the lever-arm *b¹⁸* to one of the lever-arms *e⁴*, as shown in Fig. 4.

C, Fig. 6, represents the curved pipe-section before referred to, the outer end of which is united to section B and the inner end to section D, as shown.

c represents an enlargement upon the vertical position of the pipe-section, which is provided at the base of its interior chamber with a semi-spherical recess adapted to hold the brass balls *c' c'*, as shown.

D represents a vertical pipe-section having at its lower end a bearing-flange, *d*, adapted to rest upon the balls and sustain the moving portion of the stand-pipe.

d' represents a packing-ring, by means of which packing may be applied to the pipe at this point to make a water-tight joint.

E, Figs. 5 and 6, represents a vertical pipe-section extending from the upper end of section D to the lower end of the curved upper section, F, as shown, which section is provided with an overhanging flange, *e*, as shown in Fig. 1.

e' represents a conical section or base-piece bolted to the platform of the stand-pipe, the upper edge of which projects into the recess of the flange *e* for the purpose of maintaining the stand-pipe in its proper vertical position.

e², Figs. 5 and 6, represents a sleeve or collar upon the pipe E, which is capable of free movement in a vertical direction, and *e³ e³* parallel rods, the lower ends of which are attached to the collars in any proper manner, and the upper ends of which extend upward through the adjacent flanges of the pipe-sections E F to the rods *ff* upon the pipe-section F, as shown in Figs. 1 and 3.

e⁴ e⁴ represent horizontal levers, the rear ends of which are supported by the cross-bar

a³, before referred to, and the front ends of which are held between the flanges of the collar *e²*, as shown in Fig. 6.

f', Figs. 1 and 3, represents the transverse shaft of a bell-crank lever, held by proper bearings on the pipe-section F, which is provided with the single central arm, *f²*, and the two side arms, *f³ f³*, as shown.

f⁴ represents a horizontal arm extending from the pipe-section F, upon which is located the adjustable counterbalance-weight *f⁵*, as shown.

G represents a pipe-section extending forward in a horizontal plane from the upper end of the curved section F, which is provided with a curved discharge end, *g*, as shown.

H represents a bell-crank lever held by proper bearings on the front end of pipe-section G, the short arm *h* of which is united by means of the connecting-rod *h'* to the long arm *f²* of the bell-crank lever on pipe-section F.

The operation of the described construction is substantially as follows: When it is desired to use the stand-pipe the horizontal arm of the same is swung over the tender in the manner well understood, the moving part of the stand-pipe turning readily on the friction-balls *c' c'*. The actuating-lever H is then moved by the fireman from its normal position (shown in Fig. 3) to the position shown in Fig. 9. By

means of this action the valve is opened, as shown in dotted lines, Fig. 6, and full lines, Fig. 7, through the intermediate mechanism described, and the water consequently is permitted to flow from the main through the stand-pipe and out into the tender. When the proper supply has been obtained the lever H is moved back again to its normal position (shown in Fig. 3) to close the valve and stop the flow.

When the actuating-lever H is in the position shown in Fig. 9 it is locked against an accidental return movement, the connecting-point of the lever being practically behind the base of resistance, so that movement cannot occur until the same has been lifted vertically. When the actuating-lever is moved to open the valve the first portion of its action moves the adjacent end of the connecting-rod *h'* more in a vertical direction than

in a horizontal, and the subsequent portion of its action moves the connecting-rod more in a horizontal direction than in a vertical. From this it follows that the valve will be opened slowly in starting and more quickly afterward.

The person also who actuates the lever uses his power more effectively in starting the valve from its seat. The movement of the valve also in returning to its seat is eased by the action of the cylinder *b⁶*, which compels gradual movement by the gradual escape of the water contained therein through the loose-fitting joint.

By the employment of this device and the safety-valve all injury from shock is avoided when the valve is closed. The main valve, it will be observed, is balanced, so that no great

120
125
130

resistance to movement exists. The same action that closes the main valve opens the waste-cock, so that the water shut into the stand-pipe is permitted to escape.

5 Some of the advantages of the described construction are as follows: By the employment of the cylinder b^6 the movement of the valve is arrested in closing for the purpose of preventing sudden shock. By means of the 10 special construction of the actuating mechanism the valve is readily moved from its seat, and when moved is automatically held in its open position. By means of the special location of the valve it may be readily reached 15 without dismounting any portion of the structure.

Having thus fully described my invention,

what I claim as new, and desire to secure by Letters Patent, is—

1. In combination with the valve having the 20 recess b^8 , the loose-fitting cylinder b^6 and the valve-seat b^2 , substantially as and for the purpose described.

2. In combination with the rock-shaft f' and the connections f^2 and h' , the lifting-rods 25 f , substantially as described, adapted to swing past the center, as shown in Fig. 9, for the purpose of locking the valve.

This specification signed and witnessed this 20th day of May, 1882.

JOHN B. COLLIN.
